UNITED STATES PATENT OFFICE.

THORVALD J. PETERSEN, OF NEW YORK, N. Y., ASSIGNOR TO ISIDOR ROSENBLATT, OF NEW YORK, N. Y., DOING BUSINESS AS GLOBE LIGHTING FIXTURE MANUFACTURING CO.

DESIGN FOR A LIGHTING-FIXTURE BRACKET OR ARTICLE OF SIMILAR NATURE.

Application filed June 3, 1927. Serial No. 22,311. Term of patent 3½ years.

To all whom it may concern:

Be it known that I, THORVALD J. PETERSEN, a citizen of the United States, and a resident of the city, county, and State of New York, have invented a new, original, and ornamental Design for a Lighting-Fixture Bracket or Article of Similar Nature, of which the following is a specification, reference being made to the accompanying drawing, forming a part hereof.

The figure in the drawing shows a front elevational view of the lighting fixture bracket or article of similar nature.

I claim:

The ornamental design for a lighting fixture bracket or article of similar nature substantially as shown.

THORVALD J. PETERSEN.
